APPARATUS FOR LAUNDERING

**Ezekiel J. Wilson, East Greenbush, and
John McCreary, Cohoes, N. Y.**

Application April 18, 1931, Serial No. 531,206
Renewed May 14, 1936

8 Claims. (Cl. 68—37)

For a detailed description of the present form of our invention, reference may be had to the following specification and to the accompanying drawing forming a part thereof, wherein

5 Fig. 1 shows the apparatus as a whole;
Fig. 2 is a plan of the belt with articles in place;
Fig. 3 shows a modification;
Fig. 4 shows a detail.

10 Our invention relates to a method and ma-
chine for continuous washing or laundering.
They may also be used for dyeing, drying and
other analogous operations. Primarily they are
intended for general laundering and are designed
15 for washing simultaneously articles of different
shapes, kinds and colors, in a flat or spread-out
condition and, besides washing or cleaning them,
the same machine in one continuous operation
will rinse them, sour them, extract the water and
bleach them while still on the same carrier belt.

20 The invention is in the nature of an improvement
on the method and apparatus appearing in the
patent of Ezekiel J. Wilson, No. 1,568,259, granted
January 5, 1926. In that patent the device is
only shown as adapted for the washing of a
25 single article, to-wit, the continuous felt of a
paper-making machine, but it discloses the fun-
damental method of washing by directing the
water or cleansing fluid through a traveling ar-
30 ticle from one side of said article to the other,
which method is also followed in our present in-
vention.

In laundering work of the type which our present invention is designed to perform, the practice heretofore has been to divide the mass of articles comprised in the miscellaneous lot into several distinct groups, each group being washed separately while the individual articles are crumpled together in a separate wad or bunch. The several groups thus segregated are the following: (1) Fugitive colors; (2) Hot water colors; (3) Woolens; (4) Whites; (5) Blacks; (6) Cold-water colors. Each of these six groups has some characteristic which makes necessary its separate washing apart from any other group. For example, articles of a color which is not fixed would stain white articles if washed in the same group therewith. Woolens will shrink if rubbed or agitated in hot water, although such rubbing or agitation is normal and safe with cotton goods, and so on. Moreover, each of the several groups is ordinarily washed by itself in a washer of the "cylinder" type which has ribs on its inside and is rotated for a few turns in one direction then reversed and given an equal number of turns in the opposite direction. This work occupies from

an hour to an hour and twenty minutes, and, because of friction, requires careful handling, particularly with articles that are worn or delicate and with woolens and fugitive colors. Each group is subjected to three or more soapy baths and, at least, an equal number of rinsings. With woolens and colors the machine is stopped about half the time. The stopping periods are shorter with other goods which can be kept rotating in the machine while the water is being dumped out and replaced. After the first rinsing, white fabrics usually require bleaching. The bleaching chemical has heretofore been put into the water containing the goods and acts to oxidize the dirt or dark stains therein. Several rinsings are then required to remove the bleaching agent. For colored goods, and also for other fabrics, it has been necessary, in order to absolutely neutralize the alkali in the soap, to introduce into the bath containing the articles, an acid solution called a "sour" and several rinsings are needed to remove the sour. Next in the prior-art process the mass of articles is pulled out of the cylinder and dumped on a truck which takes them to the "extractor" which, by some form of centrifugal action, removes most of the water. In this operation the clothes themselves act as a filter for the dirty water and the dirt is largely left deposited on them. The clothes also become packed so tightly in the extractor that it is difficult to remove them and yet such packing is required before starting, in order to prevent the tearing or pulling apart of the garments by the centrifugal force. In consequence, deep wrinkles are formed in the clothes which are difficult to remove and they also become knotted and entangled. In some cases the clothes are packed in separate bundles or nets which are often contained in separate pockets in the machine but no bundle is washed individually and the germs or dirt from each bundle is spread throughout all the other bundles in the machine. As a practical matter the washing is usually performed at from 140 to 160 degrees of temperature, although 212 degrees is the temperature required for real and complete sanitation.

We have thus outlined the prior laundry proceeding in order to illustrate the radical difference therefrom of our present invention. We apply or feed the clothes side by side to a wide carrier belt, or rather, between two carrier belts of wire mesh, or other material, on which the clothes are individually spread out flat. They maintain that relative position in which they are first placed through the entire series of opera- 55

tions from washing to extracting. While in that fixed position with respect to the carrier belt the water is applied to them on one side and removed from them on the other side. Thereby 5 each garment is, in effect, washed individually without chance of contamination from any other garment. All kinds and colors can be treated simultaneously, lying side by side on the same carrier belt. If a color is washed out of some 10 garment that color is removed immediately and can not come in contact with any other garment to stain it, while woolens, since they remain in a definite position on the belt, will not shrink. The water may be delivered on them directly from a 15 faucet and will therefore have no opportunity to become chilled below its temperature of 212 degrees. Its temperature and amount are also easily controllable for each garment. Each individual garment is held flat on the carrier belt without 20 wrinkles and can not become knotted in itself or entangled with another garment. This also effects a large saving in bleaching and souring materials, since the amount used is proportioned to individual garments. In our treatment the 25 clothes are not dumped into a body of water with a mass of other clothes therein, but water is sprayed or showered on the several garments individually to an amount adjusted to each. While the articles are still on the belt they may be 30 also dried. It is also possible to discharge the goods directly from the carrier belt to the ironer, after the water extraction, without crumpling or handling them except, perhaps, to direct them to the correct place on the ironer.

35 Referring to the drawing, A represents a continuous carrier belt, preferably of wire mesh, having openings of a correct size or number. While fine-meshed belts produce more perfect laundering, they may present too great a retardation of 40 the water flow through them. Therefore the mesh is usually of an intermediate size. B represents a similar but longer carrier belt that runs in contact with belt A over a portion of the course,—to-wit—through the squeeze-rolls a^1 , a^2 , a^3 and 45 the guide rolls b^1 and b^2 . The carrier belts may, however, be in contact for a longer portion of the course, if desired. The clothes to be washed are laid out flat on the lower carrier belt B preferably at a point over the drive-roll c^1 and then 50 are immediately gripped between the two belts and drawn forward as shown in Fig. 2. The clothes thus maintain their relative positions on the belts till they pass the squeeze-rolls a^3 — a^3 and thereafter will adhere, by suction, to the lower 55 belt in their same relation until they pass the second drive-roll c^2 and are delivered on to the ironer, C.

From the rolls a^1 — a^1 the carrier belts first 60 transport the fabrics to the tank D^1 wherein they pass the guide-roll b^1 and pass out to the squeeze-rolls a^2 — a^2 . As they pass the roll b^1 they are subjected to a flow of soapy water or detergent 65 directed on them from the under side in the space between the partition walls d — d . This water may be applied either as a heavy spray or as a stream, constituting in either case a flow of water directed against one side of the fabrics and through 70 them into the space outside of the said partitions d — d where it is drawn off from the bottom of the tank by the pipes k — k . It will be observed that the partitions d — d provide an open-topped sub-chamber over which the belts pass in such manner as to act as a cover therefor. Any suitable pump E may be employed to forcibly apply the 75 water and subsequently withdraw it from the main

chamber D after passing through the belts. On its way from pump E to the tank the water may pass through a heater P, as shown at the right of Fig. 1. If desired, the water may be applied, as shown in Fig. 3, from nozzles w — w located above the carrier belts and directed downward through the fabrics into the bottom of the tank. This first treatment of the fabrics is the cleansing one, being made with soapy water, which acts to dislodge and remove the dirt. After emerging from tank D^1 the belts carry the washed articles 10 consecutively through the squeeze-rolls a^2 — a^2 which remove from them such dirt as may not have been removed by the flow of the soapy water through them. It may be observed that, whereas the prior 15 methods relied on the agitation of the fabrics by the rotating ribs in the cylinder, the fabrics being at the time submerged in a body of soapy water contained in the cylinder, we rely on a water-flow directed through the outspread garments on the 20 carrier belts. By this means we have quite as effective a cleansing means and, in addition, remove the water and the dirt which the water has washed out of the garments. Thus the garments are not swashed around in a mass of dirty water, 25 with the dirt particles passing repeated into them and liable to be redeposited on them, while the garments act like filter cloths to gather such dirt particles from the water. On the contrary, only clean water is applied to the goods and the dirt 30 particles are carried away instead of being repeatedly applied to them, and by them filtered out of the water. This principle, however, does not mean that, if required, the same washing water after being cleaned, if desired, by filtering and 35 also reheated, may not be repeatedly passed through the fabrics to completely dislodge the dirt, but it may become only a flow of entirely fresh water at each passage of water through the fabrics. Next the outspread fabrics on the carrier 40 belts are transported to a second tank D^2 where, just as in tank D^1 , water is again flowed upon and through the fabrics and again carried away, said tank D^2 also having a sub-chamber similar to that of tank D^1 . This water is, however, not soapy 45 washing water, but a clean rinsing water. Its function is to remove any soap and dirty water that may have been absorbed in the washing process. Then the carrier belts pass between the squeeze-rolls a^3 — a^3 , which remove from the fabrics the bulk of the rinsing water. Here also it is possible to apply repeatedly a flow of fresh clean water to dilute any remnant of washing water, 50 which is the essential purpose of the rinsing operation. If desired, the carrier belts may be 55 passed through one or more additional tanks similar to tanks D^1 and D^2 . By this time the still wet fabrics will adhere to and may be carried by the lower belt B alone and the upper belt A may, at this point, turn back to rejoin belt B at the 60 rolls a^1 — a^1 .

From the foregoing it will be understood that the belt B is considerably longer than the belt A and that they are held in contact with each other at positions adjacent one end of the 65 apparatus. The contacting portions are caused to travel in undulations so as to be dipped into the tanks D^1 and D^2 , the smaller belt being so disposed that at the points of separation of the belts the upper belt is provided with inclined portions upwardly disposed with respect to the plane 70 of the top portion of the belt B. The arrangements also is such that the belt B has two horizontal stretches, one being longer than the other, the short stretch extending from the drive roll 75

C¹ to the squeeze-rollers A¹, and the other or longer stretch extending from the rollers A³ to the drive roll C². The garments may be stripped from the returning carrier belt A by any suitable means, such as an air blast from a nozzle F¹. The fabrics are then carried to and passed over the perforated surface of a suction box G¹ above which is a nozzle G² that delivers a souring solution on such of the fabrics as may require it. Thereby only such an amount of souring agent is used as may be needed and only such articles as require it may be soured. This is in contrast to the prior method of putting a large amount thereof, without discrimination, into a large body of water in a washing machine or tank. The suction on box G¹ is maintained by a pump H. The suction box pulls the solution through the goods and permits its recirculation. I may also employ a surface suction device M, Fig. 4, to draw from the water in D¹ or D² any layer of soap or dirt that may float on top of the water. The goods are then transported over a similar suction box I¹ above which is a nozzle I² that sprays clean water on them to remove therefrom the excess souring or acid solution. A third suction box J¹, with a nozzle J², above it, applies a size or starch to such fabrics as may require it, which then pass under a bleacher L, having an additional suction box K¹ and are finally delivered to an ironer, or to a drying machine C.

In the foregoing series of operations the rate of progress of the carrier belts will remain uniform and the time of one individual operation will be adjusted by extending or shortening the length of the action of any individual apparatus in order to continue the operation for any desired length of time under the given rate of belt progress.

What we claim as new and desire to secure by Letters Patent is:

- 40 1. A laundering apparatus comprising a foraminous carrier belt, a second shorter foraminous belt, means for imparting independent travelling movement to the respective belts, means for maintaining a portion of the shorter belt in contact with a coextensive portion of the carrier belt in such manner that the contacting portions travel together a predetermined distance, said travel imparting means being so arranged as to cause the contacting portions to travel in a common direction so that the articles to be laundered may be interposed between said contacting portions and caused to travel therewith in a flattened, spread-out condition, a laundering tank having an internal open-topped sub-chamber therein, means for causing the contacting portions of the belt to travel through said tank and over the top of said sub-chamber, means associated with said sub-chamber for forcing washing fluid through the contacting portions of the belt and the articles carried thereby during their travel through the tank and over said sub-chamber, and means for causing feeding and delivery portions of the carrier belt to travel in horizontal rectilinear courses at locations outside of the sphere of operation of the shorter belt.
- 45 2. A laundering apparatus comprising a foraminous carrier belt, a second shorter foraminous belt, means for imparting independent travelling movement to the respective belts, means for maintaining a portion of the shorter belt in contact with a coextensive portion of the carrier belt in such manner that the contacting portions travel together a predetermined distance, said travel imparting means being so arranged as to cause the contacting portions to travel in a common direction so that the articles to be laundered may be interposed between said contacting portions and caused to travel therewith in a flattened, spread-out condition, a laundering tank, a rinsing tank, means for causing the contacting portions of the belt to successively travel through the laundering and rinsing tanks, means associated with said tanks for forcing washing fluid and rinsing fluid respectively through the contacting portions of the belt and the articles carried thereby during their travel through the tanks, and means for causing feeding and delivery portions of the carrier belt to travel in horizontal rectilinear courses at locations beyond the sphere of operation of the shorter belt, one or more suction boxes positioned beneath the delivery portion of the carrier belt, and independent means above each suction box for forcing a liquid garment-treating agent through selected articles as they pass said supply means and in such man-

direction so that the articles to be laundered may be interposed between said contacting portions and caused to travel therewith in a flattened, spread-out condition, a laundering tank having an internal open-topped sub-chamber therein, a rinsing tank and also having an internal open-topped sub-chamber therein, means for causing the contacting portions of the belt to successively travel through the laundering and rinsing tanks, and over the top of said sub-chamber, means associated with said sub-chamber for forcing washing fluid and rinsing fluid respectively through the contacting portions of the belt and the articles carried thereby during their travel through the tanks and over the respective sub-chambers, and means for causing feeding and delivery portions of the carrier belt to travel in horizontal rectilinear courses at locations outside of the sphere of operation of the shorter belt.

3. A laundering apparatus comprising a foraminous carrier belt, a second shorter foraminous belt, means for imparting independent travelling movement to the respective belts, means for maintaining a portion of the shorter belt in contact with a coextensive portion of the carrier belt in such manner that the contacting portions travel together a predetermined distance, said travel imparting means being so arranged as to cause the contacting portions to travel in a common direction so that the articles to be laundered may be interposed between said contacting portions and caused to travel therewith in a flattened, spread-out condition, a laundering tank having an internal open-topped sub-chamber therein, a rinsing tank and also having an internal open-topped sub-chamber therein, means for causing the contacting portions of the belt to travel an undulatory course, means for successively forcing washing and rinsing fluids through the articles while travelling through the tanks and over the respective sub-chambers in said undulatory course, and means for causing feeding and delivery portions of the carrier belt to travel in horizontal rectilinear courses at locations beyond the sphere of operation of the shorter belt.

4. A laundering apparatus comprising a foraminous carrier belt, a second shorter foraminous belt, means for imparting independent travelling movement to the respective belts, means for maintaining a portion of the shorter belt in contact with a coextensive portion of the carrier belt in such manner that the contacting portions travel together a predetermined distance, said travel imparting means being so arranged as to cause the contacting portions to travel in a common direction so that the articles to be laundered may be interposed between said contacting portions and caused to travel therewith in a flattened, spread-out condition, a laundering tank, a rinsing tank, means for causing the contacting portions of the belt to successively travel through the laundering and rinsing tanks, means associated with said tanks for forcing washing fluid and rinsing fluid respectively through the contacting portions of the belt and the articles carried thereby during their travel through the tanks, and means for causing feeding and delivery portions of the carrier belt to travel in horizontal rectilinear courses at locations beyond the sphere of operation of the shorter belt, one or more suction boxes positioned beneath the delivery portion of the carrier belt, and independent means above each suction box for forcing a liquid garment-treating agent through selected articles as they pass said supply means and in such man-

ner as not to affect any adjacent successively following article.

5. A laundering apparatus comprising a foraminous carrier belt, a second shorter foraminous belt, means for imparting independent travelling movement to the respective belts, means for maintaining a portion of the shorter belt in contact with a coextensive portion of the carrier belt in such manner that the contacting portions 10 travel together a predetermined distance, said travel imparting means being so arranged as to cause the contacting portions to travel in a common direction so that the articles to be laundered may be interposed between said contacting portions and caused to travel therewith in a flattened, spread-out condition, a laundering tank, a rinsing tank, means for causing the contacting portions of the belt to successively travel through the laundering and rinsing tank, means associated with said tanks for forcing washing fluid and rinsing fluid respectively through the contacting portions of the belt and the articles carried thereby during their travel through the tanks, means for causing feeding and delivery 25 portions of the carrier belt to travel in horizontal rectilinear courses at locations beyond the sphere of operation of the shorter belt, a plurality of suction boxes positioned in alignment beneath the delivery portion of the carrier belt, a 30 bleacher located over the carrier belt and directly above one of said suction boxes, and independent means above the belt and over each of the other suction boxes for forcing a liquid garment-treating agent through selected articles as they 35 pass said respective supply means, and in such manner as not to affect any adjacent successively following article.

6. A laundering apparatus comprising an endless foraminous belt, drive rolls supporting said belt, a laundering tank near one of said drive rolls, a second shorter belt, drive rolls supporting the second belt above the first belt, means for maintaining the lower portion of the shorter belt in contact with a co-extensive length of the upper 45 portion of the longer belt, so that the articles to be washed will be transported with and between the contacting belts, said last mentioned means being so constructed and arranged as to cause the contacting belts to travel an undulatory course 50 and to pass through said tank, means associated with said tank for forcing washing fluid through the contacting portions of said belts and the articles carried thereby during travel of the belts through the tank, means for causing said belts to 55 separate at the end of the undulatory course, means for causing a substantial portion of the

longer belt to travel in a rectilinear horizontal course from the point of separation of said belts to the other drive roll for said longer belt, whereby the laundered articles may be subjected to finishing treatments while carried by the horizontally travelling portion of the larger belt. 5

7. A laundering apparatus comprising an endless foraminous belt, drive rolls supporting said belt, a second shorter belt supported above the first belt, said shorter belt having its lower portion engaging a corresponding co-extensive portion of the lower belt at a position between the drive rolls so that articles to be washed will be transported with and between the contacting belts, means for causing washing fluid to be forced through the contacting portions of the belts and the articles carried thereby during travel of the belts, said shorter belt being so constructed and arranged as to provide an upwardly travelling portion leading from the lower belt so 10 as to separate the same, and means adjacent said upwardly travelling portion for disengaging laundered articles which may adhere thereto after separation of the belts. 15

8. A laundering apparatus comprising an endless foraminous belt, drive rolls supporting said belt, a second shorter belt supported above the first belt, said shorter belt having its lower portion engaging a corresponding co-extensive portion of the lower belt at a position between the 20 drive rolls so that articles to be washed will be transported with and between the contacting belts, means for causing washing fluid to be forced through the contacting portions of the belts and the articles carried thereby during travel of the 25 belts, said shorter belt being so constructed and arranged as to provide an upwardly travelling portion leading from the lower belt so as to separate the same, means adjacent said upwardly 30 travelling portion for disengaging laundered articles which may adhere thereto after separation of the belts, said longer belt being so constructed and arranged as to provide a substantially long horizontal stretch from said upwardly travelling portion of the shorter belt, and means arranged 35 adjacent to said horizontal stretch to selectively treat each article to any one or more laundering agents adapted to the laundering characteristics 40 of the article, said means being so constructed and arranged that the individual agents are applied in such manner that other articles adjacent the particular one being treated are not affected 45 by such treatment. 50
